United States Patent Office

Des. 215,129
Patented Sept. 2, 1969

215,129

HAIR CURLER

Henry J. Talge, Kansas City, Mo., assignor to The Songrand Corporation, a corporation of Missouri

Filed Dec. 1, 1967, Ser. No. 9,608

Term of patent 14 years

Int. Cl. D28—03

U.S. Cl. D86—10

Fig. 1.

Fig. 4.

Fig. 2.

Fig. 5.

Fig. 3.

Fig. 6.

FIG. 1 is a top plan view of a hair curler showing my new design;

FIG. 2 is a side elevational view thereof, the row of teeth shown at the center being similar to those shown at the sides and the side of the hair curler opposite that shown being substantially identical thereto;

FIG. 3 is a bottom plan view;

FIG. 4 is a top plan view of a second embodiment of the design shown in FIG. 1;

FIG. 5 is a side elevational view thereof wherein a solid rib is embossed on the surface at the center, the side of the hair curler not shown being substantially identical to that shown; and

FIG. 6 is a bottom plan view thereof.

I claim:

The ornamental design for a hair curler, as shown and described.
